BEVERAGE DISPENSER

George H. Light, Coral Gables, Fla.

Application August 16, 1950, Serial No. 11,791

Term of patent 3½ years

(Cl. D2—3)

To all whom it may concern:

Be it known that I, George H. Light, a citizen of the United States, residing at Coral Gables, State of Florida, have invented a new, original, and ornamental Design for a Beverage Dispenser, of which the following is a specification, reference being had to the accompanying drawing, forming a part hereof.

The figure is a perspective view of a beverage dispenser showing my new design.

The other side and rear, not shown, are substantially like the side shown.

I claim:

The ornamental design for a beverage dispenser, as shown and described.

GEORGE H. LIGHT.
